IGNITING DEVICE

Henry Singer, Honolulu, T. H.

Application January 5, 1943, Serial No. 471,339

6 Claims. (Cl. 67—6.1)

This invention relates to an igniting device and it is an object of the invention to provide a device of this kind of a pyrophoric type which in its use substantially eliminates flash annoyance and fire risk.

It is also an object of the invention to provide a device of this kind which operates to provide for a continuous shower of sparks to assure positive lighting.

The invention also has for an object to provide a device of this kind especially designed and adapted for use in the lighting of gas, fireplaces, stoves, camp fires and the like and wherein the device is of a character to assure the fingers of the user being at a positively safe distance away from the suddenly ignited flame to avoid accidental scorching and burning which often occurs when using matches or short mechanical lighters.

The invention consists in the details of construction and in the combination and arrangement of the several parts of my improved igniting device whereby certain important advantages are attained, as will be hereinafter more fully set forth.

In order that my invention may be better understood, I will now proceed to describe the same with reference to the accompanying drawing, wherein:

Figure 1 is a view in elevation, with portions broken away, of a lighter constructed in accordance with an embodiment of my invention.

Figure 2 is a detailed sectional view taken substantially on the line 2—2 of Figure 1, looking in the direction of the arrows.

Figure 3 is a detailed sectional view taken substantially on the line 3—3 of Figure 2, looking in the direction of the arrows, and

Figure 4 is a detailed sectional view taken substantially on the line 4—4 of Figure 1, looking in the direction of the arrows.

As disclosed in the accompanying drawing, 1 denotes an elongated shaft which is freely disposed through the aligned tubular members 2 and 3 of desired lengths. The inner or opposed ends of these members 2 and 3 are spaced apart a desired distance but are tied or connected by a rigid coupling member 4 and which effectively maintains the members 2 and 3 in desired spaced relation.

The intermediate portion 5 of this coupling member 4 is outwardly offset, as indicated in Figure 1, to accommodate the beveled pinion 6 fixed to the shaft 1 for rotation therewith. This pinion 6 meshes with a gear 7 rotatably mounted on an outstanding trunnion 8 carried by the inner

or lower tubular section 3. The gear 7 in the present embodiment of the invention has suitably secured thereto an operating handle 9 whereby the gear may be conveniently rotated manually to effect the desired rotation of the shaft 1. The lower or inner section 3 is suitably anchored to a hand grasp 10.

The shaft 1 is of a length to extend within the outer extremity of the top or outer tubular member 2 and the shaft 1 is effectively held against undue endwise movement through the members 2 and 3 by contact of the pinion 6 with the opposed ends of the members 2 and 3. The outer or extended extremity of the shaft 1 carries a slotted head 11 adapted to engage in a conventional manner a valve member to turn or twist the same to control the flow of the gas or other fluid to the igniter.

The extended portion of the shaft 1 inwardly of but closely adjacent to the head 11 has fixed for rotation therewith a beveled pinion 12 meshing with a gear 14 fixed to the shaft 15. This shaft 15 extends outwardly and laterally from the upper or outer end portion of the tubular member 2. This shaft 15 has one end portion rotatably engaged within a bearing 16 carried externally by the tubular member 2 and is also rotatably disposed through and supported by the outer end portions of the radially opposed elongated arms 17 carried by an end portion of a flint barrel 18. This barrel 18 is parallel to the outer end portion of the tubular member 2 and spaced a slight distance therefrom but securely anchored thereto by the intermediate connecting webs 19 herein disclosed as two in number.

Fixed to the shaft 15 for rotation therewith and positioned between the arms 17 of the flint barrel 18 is an abrasive wheel 20 of desired radius and which rubs against the outer end of a flint unit 21. This unit 21 freely extends within the upper or outer end of the flint barrel 18 and is constantly urged toward the abrasive wheel 20 by the spring-pressed follower 22 working within the barrel 18, whereby the flint unit 21 is constantly urged outwardly for effective contact with the periphery of the abrasive wheel 20 and which periphery is suitably roughened.

The follower 22 is carried by the inserted end of an elongated stem 23 freely entering the lower end of the barrel 18 through a removable plug 24 closing said lower end portion of the barrel. Interposed between the applied plug 24 and the follower 22 is an expansible spring 25 of desired tension, said spring being herein disclosed as of a coil type encircling the stem 23.

Snugly engaged from above down over the webs 19 are the hook members 26 carried by the opposite end portions of an elongated split clip 27 which is adapted to frictionally hold a container 28 holding a supply of inflammable fluid and extending within this container 28 through the top of the container is a wick 29.

As is clearly illustrated in the accompanying drawing, the container 28 is positioned to one side of the plane occupied by the tubular member 2 and the barrel 18 but in relatively close proximity thereto so that the extended end portion of the wick 29 will be closely adjacent to the abrasive wheel 20 so that upon rotation of this wheel 20 by turning of the gear 7, the resultant sparks from the flint unit 21 will effect the desired lighting of the wick 29.

It is believed to be apparent that the efficiency of the device as herein disclosed is materially increased in view of the fact that the abrasive wheel 20 can be rotated for a prolonged period of time or substantially continuous to assure during such time or period the stream of sparks created will ignite the wick 29. It is also to be stated that the various gears are of such ratio to assure a rapid rotation of the abrasive wheel 20 to force the sparks downwardly for effective contact with the wick.

While in the present embodiment of the invention the container 28 is detachably engaged with a clip 21, it is believed to be obvious that if desired the hook members 26 may be carried directly by the container. As this is an obvious expedient, it is not believed necessary that such arrangement be illustrated in the drawing as to all intents and purposes, insofar as the present invention is concerned, the clip 21 and container 28 are a unit.

The lower portion of the upper tubular member 2 is herein disclosed as carrying an outwardly and laterally disposed loop member 30 to provide means whereby the device, when not in use, may be readily suspended from a wall hook or the like.

From the foregoing description it is thought to be obvious that an igniting device constructed in accordance with my invention is particularly well adapted for use by reason of the convenience and facility with which it may be assembled and operated.

I claim:

1. A portable igniting device comprising two aligned and spaced tubular members, means for connecting the opposed extremities of the tubular members, a shaft disposed through the tubular members, a pinion carried by the shaft between the tubular members, a gear rotatably carried by one of the tubular members and in driven engagement with the pinion, a flint barrel carried by one of the tubular members, a flint unit carried by the barrel, an abrasive wheel carried by the barrel for coaction with the flint unit, and an operative connection between the abrasive wheel and the shaft for rotating the wheel upon rotation of the shaft.

2. An igniter comprising an elongated tubular bearing, a shaft extending therethrough, means for turning the shaft, a handle means on the

bearing, a gear on the shaft at one end of the bearing, a flint barrel supported at one side of and from the bearing at said end, a shaft supported between the bearing and the barrel perpendicular to the first shaft and extending across an end of the barrel, a flint in and projecting from the said end of the barrel, an abrasive wheel carried upon the second mentioned shaft with its periphery in contact with the flint, a gear carried by the second shaft between the wheel and bearing and in toothed connection with the first gear, and a lamp unit including a wick supported in close proximity to the wheel.

3. An igniter as set forth in claim 2 in which said flint barrel is connected in spaced relation with the bearing by vertically spaced webs, and means carried by the lamp unit for detachable connection with said webs whereby the unit is removably mounted upon the igniter.

4. In combination in an igniter, a tubular bearing, a handle attached to the bearing at one end, a shaft extending longitudinally through the bearing and rotatably supported therein with an end extending beyond the other end of the bearing, a head carried upon the said end of the shaft and formed for detachable connection with a valve key, a gear secured to the shaft between the head and the adjacent end of the bearing, means for effecting the rotation of the shaft, and a lighter unit supported upon the bearing inwardly from the end adjacent which the gear is located, said lighter including a rotary sparking element, a lamp including a wick, and a gear connected between the first gear and the rotary sparking element for actuating the latter.

5. An igniter comprising an elongated tubular bearing, a handle secured at one end of the bearing, a shaft extending through the bearing and rotatably supported therein and projecting at one end beyond the other end of the bearing, a gear secured to the said one end of the shaft, means for rotating the shaft and gear, a flint barrel secured in parallel relation with and to the bearing inwardly from the end thereof adjacent which the gear is located, said flint barrel having longitudinally extending spaced arms and a flint in the barrel and exposed at one end between the arms, a shaft mounted between said arms to extend perpendicular to the first shaft and having an end extended between an arm and the adjacent bearing, a friction wheel supported upon the second shaft between the arms for contact with said flint, a gear secured to the second shaft between the bearing and the said one arm and having toothed connection with the first gear for transmitting rotary motion from the first shaft to the second shaft and the friction wheel, and a lamp unit including a wick supported in working proximity to the friction wheel and flint.

6. An igniter as set forth in claim 5 in which said flint barrel is connected in spaced relation with the bearing by interposed webs, a clip device having hook members adapted for detachable connection with said webs and said lamp unit being removably engaged in said clip.

HENRY SINGER.
